(57) **CLAIM**

The ornamental design for a translucent color filter, as shown and described.

DESCRIPTION

FIG. 1 is a perspective view of a translucent color filter showing our new design;

FIG. 2 is a front view thereof, the back view being identical thereto;

FIG. 3 is a right side view thereof, the left side being a mirror image thereof;

FIG. 4 is a top plan view thereof;

FIG. 5 is a bottom plan view thereof;

FIG. 6 is an enlarged sectional view thereof taken along the lines VI—VI in FIG. 4;

FIG. 7 is a perspective view thereof, the broken lines showing an electrical lead to the filter for illustrative purposes only; and,

FIG. 8 is an illustrative perspective view showing five translucent color filters, each having the claimed design, which are disposed symmetrically on a flower-shaped plate member four of the filters and the plate being shown in broken lines for illustrative purposes only.
